S. M. CURWEN.
CORNER STRUCTURE FOR CARS.
APPLICATION FILED MAY 1, 1908.

902,943.

Patented Nov. 3, 1908.

UNITED STATES PATENT OFFICE.

SAMUEL M. CURWEN, OF HAVERFORD, PENNSYLVANIA, ASSIGNOR TO THE J. G. BRILL COMPANY, OF PHILADELPHIA, PENNSYLVANIA, A CORPORATION OF PENNSYLVANIA.

CORNER STRUCTURE FOR CARS.

No. 902,943.

Specification of Letters Patent.

Patented Nov. 3, 1908.

Application filed May 1, 1908. Serial No. 430,321.

To all whom it may concern:

Be it known that I, SAMUEL M. CURWEN, a citizen of the United States, residing in Haverford, Pennsylvania, have invented 5 certain Improvements in Corner Structures for Cars, of which the following is a specification.

My invention relates particularly to that class of passenger cars in which the corner 10 posts are made so as to provide for the reception of a sliding door to extend over the platform.

In passenger cars, especially of the suburban or trolley type, the platform is a step 15 below the floor of the interior of the car and if a sliding door is used it must either extend on a level with the floor of the interior of the car or the transverse end beams of the car must be cut away for the reception 20 of the door, so as to bring the lower portion of the door on a line with the platform. It has been impossible to construct a car according to the method last described.

The object of my invention is to provide 25 a foot structure for the proper support of the end posts of the car, so that the channel for the reception of the sliding door can extend to a point on a line with the platform of the car without weakening the car at the 30 corner. This object I attain in the following manner, reference being had to the accompanying drawing, in which:—

Figure 1, is an elevation of one lower corner of a car showing the platform and illustrating my invention; Fig. 2, is a sectional view on the line 2—2, Fig. 1; Fig. 3, is a perspective view of the corner structure; and Figs. 4, 5 and 6, are detail views of the corner structure.

40 A is the body of the car having a floor *a*.
B is the platform having a floor *b*.

C is the end beam of the car which must be securely fastened to the frame of the car and to the vertical corner posts D, D'.
45 These corner posts are spaced a sufficient distance apart to form a channel *d* for the reception of a sliding door which is to inclose the platform or a portion of the platform; the lower portion of the door being 50 on a line with the platform.

In order to properly support the posts D, D' and to stiffen the corner so that it will be as strong as a solid corner, I provide a foot structure E made as clearly shown in 55 the drawing, having two vertical members

e and *e'*. In the member *e* is a socket *e²* for the reception of the lower end of the post D and in the member *e'* is a socket *e³* for the lower end of the post D'. The members *e*, *e'* are spaced apart, forming a channel *d'* 30 being a continuation of the channel *d* for the reception of the sliding door. The base E' of the foot structure is on a level with the floor *b* of the platform B so that a door arranged to slide in this channel can be projected to entirely close the platform. This is of particular advantage when the only 35 door of the car is the door that incloses the platform; the door in the end partitions separating the platform from the body of 40 the car being dispensed with.

The lower end of the socket *e³* receives the end of the transverse beam C, as clearly 45 illustrated in Fig. 1, as the corner post D extends to the base of the structure; while the post D' rests upon the beam C. The structure E has reinforcing flanges *i*, *i* which 50 act also as guides for the door and has stiffening brackets *i'* on its under side to reinforce the base plate and has a rear stiffening 55 member *i²* to give strength to the entire structure. Thus it will be seen that I can make a car structure in which I am enabled to provide a channel for a sliding door at the corner of the car without weakening the 60 car structure.

While I have shown a particular form of 65 corner structure E, it will be understood that this structure may be modified considerably, depending upon the type of car to which the 70 improvement is applied.

In the present instance the corner posts 75 D, D' are of wood and the sockets are large to receive the corner posts, but if corner posts of iron are used, then the sockets will be of 80 such a size as to receive them. The reinforcing flanges may be made of different 85 shapes.

I claim:—

1. The combination in a car, of two corner 100 posts, and a structure having two vertically projecting members spaced apart to form a continuation of the channel between the posts and adapted to receive the ends of the posts.

2. The combination in a car in which the 105 floor of the body of the car is above the floor of the platform, of a corner structure situated at the corner of the car and adapted to receive the end of the transverse beam and the corner post, and having a channel formed 110

therin extending below the floor of the car body.

3. The combination in a car, of a transverse beam at the end of the car body, a platform at the upper surface of the car bottom, two corner posts spaced apart to form a channel, and a structure having sockets to receive the corner posts and the beam, and having a channel forming a continuation of the channel between the posts and extending below the floor of the body of the car.

4. The combination in a car, of a transverse beam at the end of the car body, two corner posts spaced apart to form a channel, a structure secured to the car body at the corner and having a channel forming a continuation of the channel between the posts and extending to the platform of the car.

5. The combination of a car in which the floor of the body of the car is above the platform, a cross beam at the end of the car, two corner posts, a structure having two sockets, one socket receiving the outer side corner post, the other socket receiving the end of the transverse beam and the lower end of the inner corner post, said structure being channeled to a point about on a line with the floor of the platform.

6. The combination in a car in which the floor of the body portion is above the floor of the platform, of a transverse beam at the end of the car body, two corner posts, one supported a given distance from the other so as to form a channel for the reception of a door, a corner structure made in one piece and hav-

ing sockets for the reception of the corner posts and the beam, said sockets being spaced apart so as to form a channel, said channel extending to the floor of the platform.

7. As a new article of manufacture, a corner structure for the corner of a car made in a single piece and having two vertical members, a socket in each member, said members being spaced apart to form a channel.

8. As a new article of manufacture, a corner post for cars made to form two members spaced a given distance apart, and a base plate uniting the two members, each member having a socket for the reception of a post and braced to stiffen the structure.

9. As a new article of manufacture, a corner structure for railway cars having two vertical members spaced a given distance apart to form a channel, one member having a socket for the reception of the outside corner post, the other member having a socket for the reception of the end beam and the inside corner post, a base plate at the lower end of the structure, and two flanges projecting from the inner side of each section so as to increase the bearing surface of the section for the guidance of a door.

In testimony whereof, I have signed my name to this specification, in the presence of two subscribing witnesses.

SAML. M. CURWEN.
